UNITED STATES PATENT OFFICE

ROSS E. LANGILL AND WILLIAM B. GRUETER, OF MENOMINEE, MICHIGAN, ASSIGNEES
TO THE PRESCOTT COMPANY, OF MENOMINEE, MICHIGAN, A CORPORATION OF MICHIGAN

SAWMILL DOG

Application filed September 13, 1926. Serial No. 134,986.

This invention relates to improvements in sawmill dogs of the so-called tong type, and more particularly to the mechanism for actuating the tong arms or log-holding members.

One of the objects of the present invention is to provide a sawmill dog of the character referred to having a knee, a pair of tong or log-holding arms supported for bodily longitudinal movement in a direction transverse to the knee face whereby the respective log-engaging ends of the tong arms may be extended beyond the face of the knee a relatively great amount to grip a large log, or retracted for the purpose of holding a relatively thin board, and wherein means are provided for connecting the tong arms in such wise that upon such movement of one similar movement will be imparted to the other.

Another object is to provide, in a sawmill dog of the character referred to having a knee and a pair of tong arms supported for bodily longitudinal movement in a direction transverse to the knee face, improved mechanism for imparting such movement to the tong arms.

Another object is to provide, in a sawmill dog, improved mechanism for imparting taper movement to the knee.

Another object is to provide, in a sawmill dog of the character referred to having a knee and a tong arm supported for movement in a vertical plane into and out of log-holding position, improved means engageable by the latter for limiting upward movement thereof and providing a cushion therefor.

Other objects and advantages will herein after appear.

For the purpose of illustrating the invention, one embodiment thereof is shown in the drawings, in which

Figure 1 is a side elevational view of the improved dog, looking toward the left in Fig. 3, and partly broken away for the sake of clearness;

Fig. 2 is a side elevational view, looking toward the right in Fig. 3;

Fig. 3 is a front elevational view;

Fig. 4 is a rear elevational view;

Fig. 5 is a view similar to Fig. 4, partly in

section, the section being taken on the line 5—5 in Fig. 1;

Fig. 6 is an enlarged sectional view of the improved mechanism for imparting in-and-out movement to the tong arms, the section 55 being taken on the line 6—6 in Fig. 4;

Fig. 7 is an enlarged view, partly in section, the section being taken on the line 7—7 in Fig. 5;

Fig. 8 is an enlarged sectional view, taken 60 on the line 8—8 in Fig. 1;

Fig. 9 is a side elevational view, looking toward the left in Fig. 8;

Fig. 10 is an enlarged sectional view, taken 65 on the line 10—10 in Fig. 6;

Fig. 11 is an enlarged sectional view, taken on the line 11—11 in Fig. 1 and

Fig. 12 is a detail view in section taken on line 12—12 of Figure 1.

The sawmill dog comprises, in general, the 70 knee 10 and the upper and lower tong or log-holding arms 11 and 12 supported for movement in a vertical plane toward and away from each other and for independent in-and-out movement in a direction transverse to the 75 knee face 13 whereby the tong arms may be projected outwardly beyond the knee face to bring their respective log-engaging ends or teeth 14 and 15 to the dotted line positions shown in Fig. 1 to grip a log 16, or retracted 80 to the full line positions shown to hold a thin board 17. The log-engaging end of tong arm 11 extends loosely through a hanger 18 pivotally connected by means of a bolt 19 to a shoe 20, the head of bolt 19 having 85 a sliding fit in the channel 21 provided by the spaced parallel strips 22 secured by means of the rivets 23 to an upstanding member 24 secured in any suitable manner to the knee at one side thereof. An auxiliary tooth 25 is connected by means of the bolt 26 to shoe 20 and fitted within a recess in the latter to prevent tilting of this tooth about the bolt, the arrangement being such that upon retraction of tong arm 11 to the full line position there-

of shown in Fig. 1 the auxiliary tooth 25 operates to engage the upper edge of the board 17. The construction and manner of operation of the parts just described has been set forth in greater detail and claimed in co- 100

pending application Serial No. 83,438, filed January 25, 1926 patented August 2, 1927, No. 1,637,907, and has only been shown and described in sufficient detail to enable those skilled in the art to understand the manner in which such construction may be embodied in the present improved dog.

The rear end of the upper tong arm 11 is supported by the members or links 27 and 28 keyed at their lower ends on the rock shaft 10 29 journaled in and extending transversely of the base 30 of the knee, the upper ends of these links being pivotally mounted on the extended ends of a spindle 31 or bolt extending through this end of the tong arm.

The log-engaging end of the lower tong arm 12 passes loosely through the cylindrical portion 32 of a shoe 33 through which passes the bolt 34, the head 35 of the bolt having a 20 sliding fit in channel 21, as more clearly shown in Fig. 11. The means for supporting the rear end of the lower tong arm will be hereinafter described.

The mechanism for imparting movement 25 of the tong arms toward and away from each other into and out of log-holding position includes the rack 36 connected at its lower end by means of the pin 37 to the lower tong arm 12 at a point intermediate its ends, 30 the rack extending upwardly and loosely through a sleeve 38 mounted loosely on a shaft 39 extending transversely of and journaled at its ends in bearings 40 and 41 with which the tong arm 11 is provided. A pinion 42 is fixed on shaft 39 and arranged in mesh with rack 36 and enclosed in a housing 43 which may be cast integrally with sleeve 38. From the foregoing it will be seen that upon rotation of shaft 39 in one direction the 40 tong arms will be moved together to grip a log, while reverse rotation of this shaft will cause movement of the tong arms away from each other to release the log, such movement of the tong arms being accompanied by sliding movement of their respective log-engaging ends a slight amount in the hanger 18 and portion 32 of shoe 33 for the reason that at this time the tong arms are supported at their rear ends for pivotal movement about relatively fixed axes, as will hereinafter more clearly appear. The shaft 39 is operated by a reversible electric motor 44 fixed to the tong arm 11 at its rear end and having its armature shaft connected through a suitable 50 coupling, indicated generally by the reference numeral 45, to a worm shaft 46 journaled in a suitable bearing 47 carried by the tong arm 11 and meshing with the worm wheel 48. The worm wheel 48 is assembled over a cylindrical part 49 fixed on shaft 39, and is provided on each side thereof with a clutch ring 50 and a flange 51 secured to the gear for rotation therewith by any suitable means such as bolts 52. The worm wheel is connected to part 49 by suitable friction means

which may comprise clutch discs 53 compressed a certain amount between end flanges 51 and the spacing collar 54, alternate discs being splined at their outer edges to rings 50, the remaining and intermediate discs being splined at their inner edges to the part 49. When motor 44 is operated to cause movement of the tong arms together, the log-engaging ends or teeth 14 and 15 will engage and be embedded in the log a certain amount to properly hold the latter, at which time the clutch discs 53 will permit complete slippage of worm wheel 48 with respect to the part 49 fixed on shaft 39, thereby preventing strain on the motor which would otherwise occur. The coupling 45 may be provided with the drum 55 about which is placed a frictional brake band 56 adjusted to place an initial load on the motor. This operating means or mechanism for imparting movement of the tong arms 11 and 12 toward and away from each other is more fully shown and described in copending application Serial No. 56,590, filed September 16, 1925.

A bolt 57 is slidably fitted in a housing 58 which may be formed integrally with member 24 at the upper end thereof, as more clearly shown in Fig. 12, and a spring 59 is arranged on the bolt and compressed between the head 60 thereof and the upper end of housing 58 to oppose upward movement of the bolt. A lug 61 is arranged on bolt 57 between the nuts 62 threaded on the upper end thereof and the upper end of housing 58, the lug extending laterally of the bolt through an opening 63 in member 24 to the other side thereof into the path of movement of shoe 20. In the event that motor 44 is reversed to cause upward movement of tong arm 11 beyond that required to release the log, shoe 20 will engage lug 61 and cause slight further compression of spring 59 until the clutch discs 53 permit complete slippage of worm wheel 48, the lug 61 and its associated parts thereby providing a cushion for limiting upward movement of the tong arm 11. A suitable bracket 64 may be secured by bolts 65 to the base 30 of the knee and arranged to provide a seat or support for shoe 33 carrying the front or log-engaging end of the lower tong arm 12, the arrangement being such that the shoe seats upon the bracket 64 when tong arm 12 has been lowered sufficiently to bring the point of tooth 15 slightly below the upper face of the head block 66.

The mechanism for imparting taper movement to the knee includes the rotatable screw 67 journaled in the knee base 30 and supported against axial movement with respect thereto. Referring more particularly to Figs. 8 and 9, the nut 68 is mounted on screw 67 and fitted in a housing 69 provided with the depending lug 70 and the laterally extending and oppositely directed lugs 71, the

nut being fixed with respect to the housing by bolts 72. Levers 73 and 74 are mounted on the extended ends of the pin 75 journaled in lug 70, the levers being held in position by suitable pins 76 extending through the same and pin 75. Each of the levers 73 and 74 is provided at its upper end with an adjusting bolt 77 provided with a lock nut 78 arranged to engage the adjacent face 10 of the associated lug 71, as more clearly shown in Fig. 9. A bolt 79 is pivotally connected by means of the pin 80 to lever 74 at a point adjacent the upper end thereof, and extends loosely through the lug 71. A relatively stiff spring 81 is arranged on the bolt and compressed between lug 71 and nuts 82' threaded on the free end of the bolt. A similar bolt 82 and spring 83 is associated in like manner with lever 73. The lower ends of 15 levers 73 and 74 are spaced to receive one end of a link 84 and are connected to the latter by the pin 85, the other end of link 84 being connected by the pin 86 to the setting means or mechanism which may comprise the usual rack 87 slidably mounted on the head block 66 and arranged in mesh with the pinion 88 fixed on the set shaft 89. From the foregoing it will be seen that upon rotation of shaft 89 in a counter-clockwise direction, as viewed in Fig. 1, the rack and knee will be carried forward. In the event that a log is thrown against the knee with great force, the springs 81 and 83 will yield a slight amount to permit slight tilting of 20 levers 73 and 74 about pin 85 as a center, this yielding of the springs, however, being only momentary and providing for a cushion between the setting mechanism and the knee to relieve the parts against strain which might 25 otherwise occur if a rigid connection were provided between the nut 68 and the setting rack 87, as in constructions used heretofore. The stiffness of springs 81 and 83 is sufficient to normally hold the adjusting bolts 77 in 30 close engagement with lugs 71 under all conditions met with in actual practice, the springs yielding only momentarily to provide a cushion between the parts as explained. In retracting the knee by reversing the rotation of shaft 89, it will be seen that the connecting link 84 will be under tension and the levers 73 and 74 held against tilting or 35 pivotal movement in a counter-clockwise direction, as viewed in Fig. 9, by engagement of bolts 77 with lugs 71. By reason of the construction just described, it will be seen, further, that rotation of screw 67 in either direction will impart any desired taper movement to the knee.

For the purpose of rotating screw 67, a gear 90 is mounted on one end thereof and arranged in mesh with a similar gear 91 fixed on the shaft 92 journaled at its ends in suitable bearings 93 and 94 carried by the housing 95 at the rear end of the knee, a suit-

able reversible electric motor 96 being connected to shaft 92 through a suitable coupling 97 and connected by bolts 98 to bracket 99 fixed to the knee base by bolts 100. The gear 90 may be provided with the end flanges 101 and 102 fixed thereto and friction discs 103 disposed between these flanges, alternate discs being splined at their outer edges to gear 90, the remaining intermediate discs being splined at their inner edges to the collar 75 104 fixed on the shaft 67. The discs 103 may be held compressed in frictional engagement with each other by the ring 105 fitted loosely in a recess in the adjacent face of end flange 102 and urged to the right, as viewed in Fig. 6, by any suitable means such as springs 106 held compressed between plugs 107 screwed into the open ends of bosses 108 formed integrally with end flange 102. This construction permits of complete slippage of gear 90 with respect to its shaft when the taper nut 68 reaches either of its extreme positions along screw 67 to lock the latter against rotation whereby the motor 96 is relieved from strain which would otherwise occur. An indicator 109 may be secured to the nut housing 69 and arranged to traverse the upper serrated edge of a plate 110 fixed to the knee base 30 to indicate the extent of taper movement which has been imparted to the knee.

Members or links 111 and 112 are fixed on the ends of a rock shaft 113 journaled in and extending transversely of the knee base 30. A member or link 114 is pivotally connected at one end by the pin 115 to the upper end of member 112 and at its other end to the bolt or pin 116 extending loosely through the members 27 and 28. The member or link 117 is pivotally connected at one end by the pin 118 to the upper end of member 111 and at its other end to pin 116, member 117 being provided with the depending portion 119 pivotally connected by the pin 120 to the rear end of the lower tong arm 12. From the foregoing it will be seen that upon rotary or pivotal movement of members 27 and 28 to the left, as viewed in Fig. 1, the upper tong arm 11 will be moved bodily and longitudinally to the left to position its tooth 14 outwardly beyond the face of the knee to the dotted line position shown, and that such movement of members 27 and 28 will be accompanied by a similar movement of members 111 and 112 by reason of their connection to members 27 and 28 through links 114 and 117, and, further, that the member 117 is supported for floating movement by reason of its arrangement and connection with members 27 and 111 and will be moved bodily to the left and will be maintained in a fixed angular relation with respect to the vertical so that this forward movement of the upper tong arm will be accompanied by simultaneous and similar movement of the lower tong arm 12. It will be seen, fur-

ther, that in the means or mechanism just described for connecting the lower tong arm to the member 27 for operation thereby, for all positions of members 27, 111 and 117, lines connecting their respective points of pivotal movement, namely, 29, 113, 118 and 116, will form a parallelogram.

The means for imparting rotary or pivotal movement to members 27 and 28 for the purpose explained will now be described, referring more particularly to Figs. 6 and 10. The screw 121 is journaled at one end in the bearing 122 with which the knee is provided, collars 123 being fixed on this end of the screw on either side of the bearing, as shown, to hold the screw against axial movement while permitting of free rotary movement thereof, the other end of the screw being journaled in the bearing 124 formed integrally with the cover plate 125 secured to housing 95 by the bolts 126. The nut 127 is mounted on screw 121 and is fitted within the housing 128 provided with the depending lug 129 and the flange 130, the nut being secured to housing 128 and held against rotation with respect thereto by the bolts 131. Bolts 132 pass loosely through flange 130 and are fixed at their ends in the bolt or pin 116, springs 133 being arranged on bolts 132 and compressed between nuts 134 threaded on the outer ends of the latter and the flange 130. A guide rod 135 extends loosely through lug 129 and is supported at one end in housing 95 and at its other end in the frame plate 136 extending upwardly from and being secured to the knee base, springs 137 and 138 being arranged on rod 135 at each end thereof for the purpose hereinafter explained. Upon rotation of screw 121 in a given direction nut 127 will be caused to travel along the screw to the right to impart pivotal movement to members 27 and 28 to the right by reason of the engagement of flange 130 with pin 116, while reverse rotation of screw 121 will cause movement of the nut along the latter to the left and pivotal movement of members 27 and 28 to the left by reason of the connection between these members and the nut through bolts 132 and springs 133, the springs providing a cushion to absorb any shock which might occur. When nut 127 reaches either of its extreme positions along screw 121 lug 129 engages one of the springs 137 and 138 to compress the same, the compressed spring then acting to reduce binding action between the screw and nut and to facilitate starting of the nut along the latter upon reverse rotation of the same. For the purpose of rotating screw 121 a gear 139 is mounted on the screw shaft and arranged in mesh with a similar gear 140 fixed on the shaft 141 journaled in housing 95 and connected through the coupling 142 to the reversible electric motor 143. The motor 143 is fixed by bolts 144 to a bracket 145 secured to the knee base by

bolts 146. The construction and manner of operation of gear 139 is identical to that of gear 90, friction discs 147, similar to discs 103, permitting complete slippage of gear 139 to relieve motor 143 from unnecessary strain when the nut 127 reaches either of its extreme positions along screw 121 to lock the same against rotation.

From the foregoing it will be seen that an improved sawmill dog has been provided wherein the log-holding arms 11 and 12 may be retracted to the full line positions thereof shown in Fig. 1 in holding a thin board 17, at which time the auxiliary tooth 25 operates to engage the upper edge of the board, and wherein the arms may be readily and quickly projected to place their respective teeth 14 and 15 in the dotted line positions shown to grip a large log, and, further, that an improved sawmill dog has been provided wherein the log-holding arms may be readily and quickly operated in any desired manner to meet varying conditions as regards the size, and shape of the lumber.

While but one embodiment of the invention has been shown and described, of course various changes may be made such as in the size, shape and arrangement of the parts without departing from the spirit of the invention or the scope of the claims.

The invention claimed is:

1. In a sawmill dog having a knee and a pair of log-holding arms supported for bodily movement in a direction transverse to the knee face, means operable upon such movement of one of said arms to simultaneously impart similar movement to the other of said arms, said means including links supported for pivotal movement about relatively fixed axes, one of said links being pivotally connected to said first-mentioned arm, and a member interposed between said links and pivotally connected to the latter and to said other arm, and means for imparting said first-named movement to said first-mentioned arm.

2. In a sawmill dog having a knee and a pair of log-holding arms supported for bodily movement in a direction transverse to the knee face, means operable upon such movement of one of said arms to simultaneously impart similar movement to the other of said arms, said means including links supported for pivotal movement about relatively fixed axes, one of said links being pivotally connected to said first-mentioned arm, and a member interposed between said links and pivotally connected to the latter and provided with a depending portion pivotally connected to said other arm, and means for imparting said first-named movement to said first-mentioned arm.

3. In apparatus of the character described, a sawmill log carriage, a knee mounted thereon, mechanism for imparting setting move-

- ment to said knee, means carried by said knee for imparting taper movement thereto and including a rotatable screw and a nut mounted thereon and provided with a laterally extending lug, and means providing an operating connection between said mechanism and said taper means and including a lever connected to said nut for pivotal movement with respect thereto, a bolt extending loosely through said lug and connected to one end of said lever, and a spring arranged on said bolt between the head thereof and said lug for opposing pivotal movement of said lever in one direction.
4. In a sawmill dog, a knee provided with an upstanding member, a log-holding arm having its log-engaging end disposed on one side of said member and supported and guided thereby for vertical movement, a lug supported by said member on the other side thereof and extending transversely of the same into the path of movement of said arm for engagement thereby, and means yieldingly holding said lug against movement with said arm upon such engagement of the latter with said lug.
5. In a sawmill dog, a knee provided with an upstanding member, a log-holding arm having its log-engaging end disposed on one side of said member and supported and guided thereby for vertical movement, a bolt arranged on the other side of said member and supported thereby for similar movement, a spring arranged on said bolt and opposing upward movement thereof, and a lug carried by said bolt and extending transversely thereof to said first-mentioned side of said member into the path of movement of said arm.
6. In a sawmill dog, a knee, a log-holding arm supported thereby for movement in a vertical plane into and out of log-holding position and for independent movement in a direction transverse to the knee face, means for imparting said first-named movement to said arm, and mechanism for imparting said second-named movement to said arm and comprising a rotatable screw carried by said knee and supported against axial movement, a nut mounted on said screw and connected to said arm and held against rotary movement, and a high speed rotary motor operatively connected to said screw for rotating the same.
7. In a saw mill dog, a knee, a log-holding arm supported at its log-engaging end by said knee for movement in a vertical plane into and out of log-holding position and for independent movement in a direction transverse to the knee face, means for imparting said first-named movement to said arm, a member connected to said arm and supported for pivotal movement in said direction about an axis fixed with respect to said knee and operable upon such movement to impart said second-named movement to said arm, and mechanism for effecting said pivotal movement of said member and comprising a nut engaging the latter and supported against rotary movement, a rotatable screw extending through said nut and support by said knee against axial movement, and a motor geared to said screw for rotating the same.
8. In a sawmill dog, a knee, a log-holding arm supported at its log-engaging end by said knee for movement in a vertical plane into and out of log-holding position and for independent movement in a direction transverse to the knee face, means for imparting said first-named movement to said arm, a member connected to said arm and supported for pivotal movement in said direction about an axis fixed with respect to said knee and operable upon such movement to impart said second-named movement to said arm, and mechanism for effecting said pivotal movement of said member and comprising a rotatable screw supported by said knee against axial movement, a nut arranged on said screw for engagement with said arm, said nut being held against rotary movement and being provided with a lug, a bolt provided at one end with a stop and extending loosely through said lug and connected at its other end to said member, a spring arranged on said bolt for compression between said stop and said lug upon movement of said nut away from said member, and a rotary motor geared to said screw for rotating the same.
9. A saw mill dog having a knee, upper and lower elongated tongs, means co-acting with the forward portions of the tongs and with the knee for constraining the tongs to up and down movement toward and away from each other and for movement transverse to the knee, a swingable supporting and driving member pivoted to the knee and to the upper tong, power means co-acting with said supporting and driving member for moving the upper tong transverse to the knee, and means co-acting with the supporting and driving member and providing a parallel link motion between the supporting and driving member and the lower tong for constraining the lower tong to move transverse to the knee when the upper tong is correspondingly moved.
10. A saw mill dog having a knee, upper and lower elongated tongs, means co-acting with the forward portions of the tongs and with the knee for constraining the tongs to up and down movement toward and away from each other and for movement transverse to the knee, a swingable supporting and driving member pivoted to the knee and to the upper tong, power means co-acting with said supporting and driving member for moving the upper tong transverse to the knee, a link pivotally supported on the knee and disposed parallel to the swingable sup-

- porting and driving member and a T-shaped member pivotally connected to the link, to the swingable supporting and driving member and to the lower tong for constraining the lower tong to partake of straight back and forth movement transverse to the knee when the upper tong is correspondingly moved.
11. A saw mill dog having a knee, upper and lower elongated tongs, means co-acting with the forward portions of the tongs and with the knee for constraining the tongs to up and down movement toward and away from each other and for movement transverse to the knee, a swingable supporting and driving member pivoted to the knee and to the upper tong, power means co-acting with said supporting and driving member for moving the upper tong transverse to the knee, and means directly connected with the supporting and driving member and actuated therewith for constraining the lower tong to move back and forth transverse to the knee when the upper tong partakes of a corresponding movement.
12. A power saw mill dog of the tong type comprising a knee having a face, upper and lower elongated tongs associated with said knee and movable toward and away from each other and transverse to the knee face and a parallel link motion between said tongs for constraining one of the tongs to move back and forth transverse to the knee face when the other tong is correspondingly moved, said parallel link motion being at the rear end of the tongs so that the tongs may project without obstruction between them well beyond the face of the knee.
13. In a saw mill dog, a knee having a guideway, a log holding arm, a shoe having means slidably receiving said arm, a laterally projecting member connected with the shoe and operating in the guideway and means mounted on the knee and engageable with the under side of the shoe to limit the downward movement of the shoe.
14. A power saw mill dog of the tong type comprising a knee having a face, upper and lower elongated tongs, means co-acting with the forward portions of the tongs and with the knee for constraining the tongs to up and down movement toward and away from each other and for movement transverse to the knee face, a supporting and driving member pivoted to the knee and to the upper tong, an electric motor mounted on the knee, a screw driven from the electric motor, means for holding the screw against axial movement while permitting it to rotate, a traveling nut engaged with the screw, a connection between the traveling nut and the supporting and driving member and means for constraining the lower tong to move transverse to the knee face when the upper tong is correspondingly moved.
15. A saw mill dog having a knee, upper and lower elongated tongs, means co-acting with the forward portions of the tongs and with the knee for constraining the tongs to up and down movement toward and away from each other and for movement transverse to the knee, a swingable supporting and driving member pivoted to the knee and to the upper tong, power means co-acting with said supporting and driving member for moving the upper tong transverse to the knee, and means connected with the supporting and driving member at a point spaced from its pivotal connection to the upper tong and actuated therewith for imparting to the lower tong back and forth movement transverse to the knee of different amplitude from that imparted to the upper tong.
16. A power sawmill dog of the tong type comprising a knee having a face, upper and lower elongated tongs associated with said knee and movable toward and away from each other and transverse to the knee face, means for moving the tongs toward and away from each other, and means for moving the tongs transversely to the knee face and including a parallel link motion interconnecting said tongs for constraining one of the tongs to move back and forth transverse to the knee face when the other tong is correspondingly moved.

In witness whereof, we hereto affix our signatures.

ROSS E. LANGILL,
WILLIAM B. GRUETER.
